UNITED STATES PATENT OFFICE.

JOY CLAYTON, OF STOTTS CITY, MISSOURI.

HOLDBACK.

1,073,028.

Specification of Letters Patent. Patented Sept. 9, 1913.

Application filed April 25, 1910. Serial No. 557,484.

To all whom it may concern:

Be it known that I, JOY CLAYTON, a citizen of the United States, residing at Stotts City, in the county of Lawrence and State 5 of Missouri, have invented a new and useful Holdback, of which the following is a specification.

It is the object of the present invention to provide an improved construction of hold- 10 back for vehicle thills and the invention aims primarily to provide a holdback which may be applied to any ordinary thill and may be adjusted to any desired position thereon.

At present, such devices are in the nature 15 of strap loops which are secured permanently to the thills but which present the disadvantage of soon becoming rotted and broken, and the invention therefore aims primarily to provide a holdback for thills 20 which will not be noticeably affected by the elements and with which the holdback straps of the harness may be readily connected.

Briefly stated, the device embodying the 25 present invention is in the nature of a sleeve which is fitted upon the thill and is held in adjustment thereon by a set screw engaging through the sleeve and impinging against the thill and a ring which is carried by the 30 said sleeve and with which may be engaged a snap hook carried by the harness hold- back strap and while one form of the invention contemplates the employment of but a single ring upon the sleeve, another form of the invention embodies two rings with one of 35 which rings is to be connected a branch strap from the girth so that not only will the device serve as an attachment for the holdback strap of the harness, but also, the thills will be held in proper position with 40 respect to the draft animal.

In the accompanying drawings, Figure 1 is a perspective view of one form of the device applied to a vehicle thill. Fig. 2 is a 45 vertical sectional view through the device and the thill.

In the drawings, the thill is indicated by the numeral 5 and there is also illustrated in the drawings a holdback strap which is indicated by the numeral 6 and a strap 50 which is indicated by the numeral 7 and branches from the girth of the harness.

The device is illustrated in the drawings as including a sleeve 8 which is fitted upon the thill and is held at adjustment thereon 55 through the medium of a set screw 9 which is threaded through the upper side of the

sleeve and impinges against, or may, if desired, bite into the thill 5 whereby to hold the sleeve at the proper adjustment upon the thill. The holdback strap 6 is provided with a snap hook 10 which may be snapped into one of a pair of rings carried by the sleeve. 60

The ring mentioned is indicated by the numeral 11, whereas the other ring of the pair is indicated by the numeral 12 and both of these rings are loosely engaged through openings 13 formed in a reinforcing flange 14 which is integral with the sleeve and projects inwardly laterally therefrom. The 65 strap 7 heretofore mentioned is provided also with a snap hook which is indicated by the numeral 15 and is detachably engaged with the ring 12 which is the forward one of the two rings when the device is in proper 70 position upon the thill. With this form of the device properly applied and positioned upon the thill, the holdback straps of the harness may be readily connected to and disconnected from the rings 11 and in a like 75 manner, the straps 7 may be readily disconnected from the rings 12, it being understood that the said straps 6 perform their usual function while the straps 7 serve to hold the thills in proper position with respect to the draft animal and the harness 80 which is connected to them. As the weakest point in a thill is where the harness is attached thereto, it will be apparent that the sleeve 8 constitutes an efficient reinforce 85 at that point and the sleeve, in turn, is reinforced by the flange 14. As the sleeve is fastened to the thill by the set screw 9, it cannot pull off of the thill should the swingletree become broken. Under these conditions 90 95 the attachment can be used in pulling a vehicle uphill, thus preventing accidents such as often occur when swingletrees break when carriages are moving upgrade. By using this attachment it is not necessary to 100 wrap any straps of the harness about the thill or to use buckles or the like. Instead, 105 it is merely necessary to snap the hooks 10 and 15 into engagement with the rings 11 and 12.

The fact will be readily appreciated that by the employment of this device, not only will the frequent substitution of new holdback straps upon the thills be obviated but also, the holdback connection to the thills 110 may be adjusted by the adjustment of the device so that the connection between the

harness and the thills may be varied according to the size of the harness.

What is claimed is:

A harness attachment comprising a metallic sleeve, means adapted to hold said sleeve in rigid position upon a vehicle thill, a flange formed integral with said sleeve and extending radially therefrom, said flange provided with apertures adjacent the ends thereof, rings loosely mounted within said flange apertures, said rings adapted to be connected to the harness holdback, and

with a girth branch strap to thereby provide a holdback and to hold the vehicle thills in spaced relation with respect to the 15 draft animals.

In testimony that I claim the foregoing as my own, I have hereto affixed my signature in the presence of two witnesses.

JOY CLAYTON.
